UNITED STATES PATENT OFFICE.

CHRISTOPHER J. MEYER, OF WAUWATOSA TOWNSHIP, COUNTY OF MILWAUKEE, WISCONSIN, ASSIGNOR TO EVINRUDE MOTOR COMPANY, OF MILWAUKEE, WISCONSIN, A CORPORATION OF WISCONSIN.

PROPELLING ATTACHMENT FOR CANOES, ROWBOATS, &c.

1,234,370.

Specification of Letters Patent. Patented July 24, 1917.

Application filed September 21, 1914. Serial No. 862,650.

To all whom it may concern:

Be it known that I, CHRISTOPHER J. MEYER, a citizen of the United States, residing at the township of Wauwatosa, county 5 of Milwaukee and State of Wisconsin, have invented new and useful Improvements in Propelling Attachments for Canoes, Row-boats, &c., of which the following is a specification.

10 My invention relates to improvements in propelling attachments for canoes, row boats, etc.

The object of my invention is to provide a fitting, convenient for attachment to the 15 hull of a boat, and which is adapted to constitute a stuffing box for the propeller shaft, and a pumping connection adapted to supply water to the jacket of an internal combustion engine, and which will cover a plurality of openings in the hull in water tight 20 relation to its inner and outer walls, around such openings.

The drawing illustrates a fragment of the 25 bottom of the hull of a canoe in longitudinal section, showing my improved attachment also partially in section, drawn to a plane cutting the stuffing box and pump cylinder.

The bottom A of the hull of a canoe or 30 boat, is provided with an aperture a for the propeller shaft, another aperture a' for a pump cylinder, and a series of apertures to receive clamping bolts B. Clamping plates C and D are then fitted to the walls of the 35 hull and clamped thereto by the bolts B.

The upper clamping plate C, is provided 40 with a bearing member or bushing E which projects downwardly through the aperture a and through a corresponding aperture in the lower clamping plate D. It is also provided with an upwardly projecting cup flange C' which is internally threaded to receive a packing nut F and adapted to contain a suitable packing F'. The clamping 45 plate C also carries a cap G for a pump cylinder H, which cap is preferably formed integrally with member C and provided with an outlet nipple G' adapted to serve as a pipe or hose connection, such, for example, as the rubber tube g. Where the boat hull is of wood and the surface flat, as shown, it is possible to dispense with packing between the clamping plates and the walls of the hull. Otherwise it may be employed.

The cylinder H is provided with a plunger H' having a tubular socket H'' extending downwardly therein from its upper end, and provided with an inlet port h at its lower end, communicating with a transverse bore h', which allows water to enter the 60 cylinder H through the plunger H'. A ball valve I is seated at the upper end of the port h, and a coiled spring J is seated in the tubular socket H'' and projects upwardly above the plunger and supports a 65 cup valve seat K, provided with an outlet port K' normally closed by a gravity check valve, such as the ball L. The plunger H' is reduced in diameter where it passes through the lower end or head of the cylinder H and its range of movement is therefore limited by the cup K on the upward stroke and by the shoulder K'' on the downward stroke.

The driving shaft M is incased in a sleeve 75 M' which extends through the stuffing box and bushing and supports a casing M'' in which the propeller shaft N and gear wheels N' and N'' are mounted in operative relation to drive the propeller O. A steering 80 wing P, preferably of center board type, projects downwardly from the casing M'', and shaft N carries a cam S. Steering and reversing operations are largely performed by revolving the propeller about the axis of 85 shaft M, but the wing P facilitates these operations and aids control. The steering movements are communicated to the propeller and rudder wing P through sleeve M'. A pump operating rod O' bears on this cam 90 and extends through the wall of casing M''. It supports a ring R upon which the lower end of plunger H' bears, and as ring R encircles the sleeve M', it is obvious that it may revolve with the propeller about the 95 axis of the driving shaft, without being shifted out of pump operating relation.

I claim—

1. A clamping member for boat propeller attachments, provided with a bushing 100 adapted to receive an inclosing sleeve for a driving shaft, and also having a pump cylinder; said bushing and pump cylinder projecting from said clamping member in position for insertion through contiguous 105 apertures in the hull of a boat.

2. A clamping member for boat propeller attachments, in combination with a rotatably

adjustable driving shaft sleeve, projecting through the clamping member, a pump cylinder also extending through said member adjacent to said sleeve, an integral cap on 5 the clamping member into which said pump cylinder is secured, a plunger in said cylinder, a ring loosely encircling said sleeve, a propeller, and driving mechanism therefor extending through said sleeve, and means 10 including said loose ring for actuating the pump plunger from said driving mechanism.

3. A clamping member for boat propeller attachments, adapted to be fitted to the interior or hull of a boat, in combination with 15 a pump including a cylinder secured to the clamping member in a position to project through the hull and an actuating member extending from the cylinder, a driving mechanism carried by the hull and disposed below 20 the pump cylinder, and means associated with said driving mechanism for operating said actuating member of the pump.

4. A clamping means for boat propeller attachments, comprising a clamping plate, 25 spaced tubular members projecting from said plate for insertion through contiguous apertures in the hull of a boat, an auxiliary clamping plate provided with bearing apertures for receiving the tubular members, said 30 plate being engageable with the hull at its side opposite the first clamping plate, means for holding said plates in clamping engagement with the hull, pump mechanism in one of the tubular members, driving mechanism 35 extended through the other tubular member, and means operable by the driving mechanism outwardly of the hull for actuating the pumping mechanism.

5. A clamping member for boat propeller 40 attachments, in combination with a driving shaft sleeve projecting through the clamping member, a pump cylinder also extending through said member adjacent to said sleeve, an integral cap on the clamping member 45 into which said pump cylinder is secured, an outlet nipple extending from the cap, pump mechanism in the cylinder, driving mechanism carried by the driving shaft sleeve and adapted for disposition outwardly 50 of the hull, and means operable by the driving mechanism for actuating the pump mechanism.

6. A propeller shaft casing, provided with an axially rotatable supporting sleeve, in 55 combination with a pump actuating rod extending through the casing, and a ring rigidly connected with the rod and encircling the sleeve and adapted to engage and operate a pump plunger from any and all sides 60 of the sleeve.

7. A boat propeller attachment, including the combination with a set of inner and outer hull clamping members, of a pump and a shaft casing, each extending from the 65 upper clamping member through the lower

one, a gear casing connected with the lower end of said sleeve, a pump operating member encircling said sleeve, and connected for vertical reciprocation above the gear casing, and means for actuating said pump operating member from within the gear casing, 70 said member being adapted to engage and actuate the pump from all sides of the sleeve during rotatable adjustment of said casing about the sleeve axis. 75

8. A boat propeller attachment, including an inner hull clamping member, a pump cylinder connected therewith and provided with a valved outlet member, a tubular plunger in said cylinder, projecting through its lower end, a valve in the lower portion of said plunger, means for permitting water to enter the cylinder through the plunger when the valve is open, means for resiliently depressing the plunger, and propeller operating mechanism, provided with means for intermittently raising said plunger, substantially as described. 80

9. A boat propeller attachment, including the combination with a hull clamping member, of a set of parallel tubular projections on the hull engaging side, adapted to fit apertures in the hull of a boat; one of said projections affording a passage for propeller supporting and driving mechanism and the 90 other being adapted to receive pumping mechanism. 95

10. A boat propeller attachment, including the combination with a hull clamping member, of a set of parallel tubular projections on the hull engaging side, adapted to fit apertures in the hull of a boat,—one of said projections affording a passage for propeller supporting and driving mechanism, the other being adapted to receive pumping mechanism, together with means, operative 100 below the hull, for transmitting motion from the propelling to the pumping mechanism. 105

11. The combination with a propeller shaft casing provided with an axially rotatable supporting sleeve, of a pump including an actuating member adjacent the casing, a pump operating rod extending through the casing, and a plate carried by the rod for engaging the pump actuating 110 member and disposed at right angles to the axis of the said supporting sleeve of the casing. 115

12. A boat propeller attachment, including a rotatable propeller shaft casing, an 120 adjustably rotatable carrying sleeve projecting upwardly from said casing, a reciprocating pump actuating stem, also projecting upwardly from said casing parallel to said sleeve, and a stationary pump adapted 125 for operation by the stem in various relative positions of said stem.

13. A boat propeller attachment, including a rotatable propeller shaft casing, an 130 adjustably rotatable carrying sleeve projecting

upwardly from said casing, a reciprocating pump actuating stem, also projecting upwardly from said casing parallel to said sleeve, a ring connected with the stem and 5 encircling the sleeve, and a stationary pump including an actuating member engageable by the ring.

14. In a propeller drive the combination of a pump for supplying cooling water to 10 the engine for said drive, with means for mounting said pump in a position which is fixed relatively to said engine, a propeller shaft mounted to permit rotation for adjusting the direction of action of the propeller, and an actuating mechanism interposed between said pump and said propeller shaft, said mechanism being adapted to transmit motion from said shaft to said pump independently of the position of said 20 pump relatively to said propeller shaft.

15. In a propeller drive of the class specified, the combination of a pump which is mounted in fixed position relatively to the drive; a propeller shaft mounted to permit rotary adjustment for changing the direction of action of the propeller, and an actuating mechanism interposed between said shaft and said pump, said actuating mechanism being provided with a sliding surface adapted to transmit motion from said shaft 25 upon said pump independently of the relative position of said shaft and said pump.

In testimony whereof I affix my signature in the presence of two witnesses.

CHRISTOPHER J. MEYER.
